UNITED STATES PATENT OFFICE.

MICHAEL LIPTAK, OF ST. PAUL, MINNESOTA, ASSIGNEE TO A. P. GEHEN FIRE BRICK COMPANY, OF MEXICO, MISSOURI, A CORPORATION OF MISSOURI.

FURNACE WALL.

Application filed September 18, 1922. Serial No. 589,746.

To all whom it may concern:

Be it known that I, MICHAEL LIPTAK, a citizen of the United States, residing at St. Paul, in the county of Ramsey and State of Minnesota, have invented certain new and useful Improvements in Furnace Walls; and I do hereby declare the following to be a full, clear, and exact description of the invention, such as will enable others skilled in the art to which it appertains to make and use the same.

My present invention relates to furnace wall structures and is in the nature of a modification of or improvement on the furnace wall structure disclosed and claimed in my application Serial Number 575,737, filed of date July 17, 1922, and which application was executed of date July 14, 1922. Generally stated, the invention consists of the novel construction, arrangement and combinations of parts hereinafter described and defined in the claims.

In the drawings, which illustrate commercial embodiments of my invention, like characters indicate like parts throughout the several views.

Referring to the drawings:

Fig. 1 is a perspective showing a portion of a wall embodying my invention, looking at the wall from the interior of the furnace, some of the blocks of the wall being removed to better illustrate the construction embodied;

Fig. 2 is a fragmentary elevation looking at the inner face of the outer or permanent wall of the composite wall structure;

Fig. 3 is a perspective showing one of the lintels of the permanent outer wall structure, looking downward at the same;

Fig. 4 is a perspective of the lintel shown in Fig. 3, the same being turned upside down;

Fig. 5 is a perspective showing one of the sill blocks;

Fig. 6 is a perspective showing one of the pilasters of the permanent outer wall structure, the same being made up of two blocks and the blocks being shown as vertically separated;

Fig. 7 is a view corresponding to Fig. 2 but illustrating a slightly different arrangement of the blocks;

Fig. 8 is a transverse vertical section illustrating a modified form of the wall and showing the same connected to buckstays; 55

Fig. 9 is a perspective showing a sill block and lintel integrally formed into a channel-shaped tile, said structure being that embodied in Fig. 8;

Fig. 10 is a transverse vertical section 60 illustrating a still further modified form of the composite wall;

Fig. 11 is a perspective of one of the lintels embodied in Fig. 10; and

Fig. 12 is a perspective showing one of the sill blocks embodied in Fig. 10.

In this improved wall, as in the wall of my earlier application, the complete wall structure illustrated is made up of what may be designated as a permanent outer 70 wall and a replaceable high refractory masonry inner wall.

Describing first the construction illustrated in Figs. 1 to 6, inclusive, the numerals 13 and 14 indicate, respectively, the 75 lower and upper sections of channel-shaped tile or masonry anchor boxes in which the sections 13 serve as sill blocks and the sections 14 serve as lintels. In this arrangement, the said blocks 13 and 14 are approximately L-shaped in cross-section and their vertical webs are aligned and set together to form the backs of the anchor boxes. In the arrangement at present being considered, the end joints between the sill blocks 13 are horizontally offset in respect to the end joints between the lintels 14 and pilasters are placed on the intermediate portions of the former with the ends of the latter resting thereon. These pilasters may be afforded by blocks of different form, but, preferably, are made up of lower blocks 15 and upper blocks 16. For a purpose which will more fully presently appear, the sill blocks 13 are formed with raised ledges 17, 80 and the under-surfaces of the lintels 14 are slightly inclined outwardly or toward the outer face of the permanent wall structure. Consistent with this arrangement, the pilaster blocks 15 are formed with depressed ledges 18 that interlock with said ledges 17 and the upper blocks 16 are slightly tapered so that they fit the inclined undersurfaces of the lintels. Hence, when the wedge-

shaped blocks 16 are in position, the blocks 15 will be positively interlocked with the sill blocks. Preferably, the above noted blocks 13, 14, 15 and 16 of the permanent 5 outer wall are of high refractory material such as fire tile, but, in some instances, they might be made of less highly refractory material.

The replaceable inner wall should be made 10 up entirely of high refractory blocks, bricks or tiles, and, as shown, it comprises replaceable horizontal belts of fire bricks 19 and, between said belts, horizontal rows or courses of shelf-forming blocks or long fire bricks 15 20 placed in groups and extended from the replaceable wall into the cooperating anchor boxes formed by the sill blocks 13, lintels 14 and pilasters 15-16. As preferably designed, these shelf-forming blocks 20 have 25 the vertical cross-sections of commercial bricks, but, of course, such dimensions may be varied. To adapt them for interlocking engagement with the sill blocks, said shelf-forming blocks 20 are formed with depressed ledges 21. To hold the inserted ends of the shelf-forming blocks 20 interlocked to the sill blocks, key blocks or bricks 22 are placed on 30 top thereof and against the under-surfaces of the sill blocks. Said key blocks are preferably tapered or made slightly wedge-shaped so as to better fit them for engagement with the inclined under-surfaces of the lintels 14. In most arrangements, the shelf-forming blocks 20 will be extended 35 completely through the replaceable inner wall while the key blocks 22 will be extended only about one-half way through said replaceable wall and the spaces in horizontal line therewith are filled in by fire bricks 23 40 arranged to span the gaps between the groups of shelf-forming blocks. The spaces between the groups of shelf-forming blocks 20 are shown as filled in by fire bricks 24.

When the shelf-forming blocks are interlocked to the permanent outer wall, they afford shelves for supporting the horizontal belts 19 of the replaceable fire bricks so that any portion of one belt may be removed without disturbing any portion of an adjacent belt. Also, the arrangement described permits all of the parts of the replaceable inner wall, including the shelf-forming blocks 20, to be replaced at will without disturbing the blocks or elements of 50 the permanent outer wall. Advisably, space is left between the ends of the shelf-forming blocks 20 and the adjacent inner surfaces of the walls of the box-forming sills and lintels, so that in case said blocks 20 should 55 become fused to the sill, they can be loosened by pounding on their exposed inner ends and driving the same slightly farther into the pockets of the boxes. Also, to provide 60 for driving the key blocks 22 from working 65 positions, the vertical walls of the lintels 14

are formed with holes 23 through which a punch or similar instrument may be inserted and driven against said key blocks.

The construction illustrated in Fig. 7 is like that already described in connection 70 with Figs. 1 to 6, inclusive, except that the sill blocks 13^a, in this arrangement, are set with their joints vertically aligned with the cooperating overlying lintels and the pilasters are interposed at these joints. 75

The construction illustrated in Figs. 8 and 9 is like that illustrated in Fig. 7 except that the sills 13' and lintels 14' are integrally formed or mounted as a single unit. Also, in Fig. 8, the channel-shaped 80 boxes formed by the lintels 13' and 14' are shown as anchored to buckstays 24 by means of nut-equipped anchor bolts 25, such as illustrated in my prior application and not necessary for the purposes of this case to 85 further consider.

The modified construction illustrated in Fig. 10 involves certain of the principles of construction embodied in the construction already described and also involves certain 90 other highly important novel features, which will now appear. In this wall structure, the sill blocks 26 are laid in horizontal courses on masonry belts 27, preferably of fire brick, and said belts are built upon lintels 28 that have depending webs, the lower edges of which rest directly on intermediate portions of said sill blocks. Said sill blocks and lintels are also preferably of fire clay, or, in other words, are fire tiles. As a decidedly 95 novel feature, the outer ends of the sills 26 are projected and arranged to support interposed belts of ordinary masonry 29, preferably of common brick. The said elements 26, 27, 28 and 29 constitute parts of the so-called permanent outer wall. The sill blocks 26 and lintels 28 form channel-shaped anchor boxes that will be associated with interposed pilasters of suitable arrangement, such, for example, as illustrated in Figs. 2 and 7. The sill blocks 26 are formed with raised ledges 30 that interlock with depressed ledges 31 of replaceable shelf-forming blocks 32, which latter, like the blocks 20, constitute elements of the replaceable inner wall. 100 The numeral 33 indicates key blocks interposed between the shelf-forming blocks 32 and the under surfaces of the overlying lintels 28. The depending webs or walls of the lintels 28 are preferably provided with punch holes 34 for facilitating the driving out of the key blocks 33. In this form of the wall, both the shelf-forming blocks 32 and the key blocks 33 are made wedge-shaped or flaring toward the inner surface of the inner wall and the main body portion of the inner wall is of monolithic or molded structure 35 of fire clay or similar substance capable of being molded or cast to form and which, when hardened, will have a highly 105 110 115 120 125 130

refractory character. In this arrangement, the wedge-shaped elements 32 and 33 afford dove-tailed anchors anchored to the outer wall and to the inner wall and securely holding the two together.

5 What I claim is:

1. A wall structure made up of a masonry outer wall and a replaceable inner wall, said outer wall including channel-shaped tile anchoring boxes affording sill blocks and lintels, and pilasters interposed between the sill and lintel-forming portions of said anchor boxes, and said inner wall including shelf-forming blocks extended into and 10 anchored within said anchor boxes.

2. A wall structure made up of a masonry outer wall and a replaceable inner wall, said outer wall including channel-shaped tile anchoring boxes affording sill blocks and 15 lintels, and pilasters interposed between the sill and lintel-forming portions of said anchor boxes, and said inner wall including shelf-forming blocks extended into and anchored within said anchor boxes, 20 said channel-shaped anchor boxes being made up of upper and lower complementary sections.

3. The structure defined in claim 1 in which said pilasters are arranged in alignment with certain of the abutting end joints 30 of said anchor boxes.

4. The structure defined in claim 2 in which said pilasters are aligned under the end joints between the lintel-forming portions 35 of said anchor boxes.

5. The structure defined in claim 1 in which said pilasters are interlocked with the sill-forming portions of said anchor boxes.

40 6. The structure defined in claim 2 in which said pilasters are made up of sections, the lower of which are detachably interlocked to the sill-forming portions of said anchor boxes.

45 7. The structure defined in claim 1 in further combination with key blocks interposed between said shelf-forming blocks and the lintel-forming portions of said anchor boxes.

50 8. The structure defined in claim 2 in which the sill and lintel-forming portions

of said anchor boxes are horizontally staggered and said pilasters are rested on the intermediate portions of the sill-forming portions and under the joints between the 55 ends of the lintel-forming portions of said anchor boxes.

9. The structure defined in claim 2 in which the sill and lintel-forming portions of said anchor boxes have engaged vertical 60 webs that close said boxes at the outer side of the wall.

10. A wall structure made up of a masonry outer wall and a replaceable inner wall, said outer wall having vertically 65 spaced horizontally extended pockets and vertically spaced horizontally extended blocks with belts of masonry work supported on the outwardly projecting ends of said blocks, and said replaceable inner 70 wall having shelf-forming blocks extended into the pockets of said outer wall and supporting horizontal belts of masonry work.

11. The structure defined in claim 10 in further combination with key blocks interposed between the tops of said shelf-forming blocks and the tops of said pockets. 75

12. The structure defined in claim 10 in further combination with key blocks interposed between the tops of said shelf-forming blocks and the tops of said pockets, said shelf-forming blocks being positively interlocked to the bottoms of said pockets. 80

13. A wall structure made up of a masonry outer wall and a replaceable inner 85 wall, said outer wall having anchor-receiving pockets and said replaceable inner wall having a high refractory molded body portion and anchor blocks anchored thereto and within the pockets of said outer wall. 90

14. The structure defined in claim 13 in which said anchors are made up of shelf-forming blocks and key blocks.

15. The structure defined in claim 13 in which said anchors are made up of shelf-forming blocks and key blocks that flare into the body of the inner wall and are interlocked therewith.

In testimony whereof I affix my signature.

MICHAEL LIPTAK.
